BATTERY POWERED TAPE WINDER FOR PUNCHED PAPER TAPE AND THE LIKE

Jacob J. Ginsberg, Tewksbury, Mass., assignor to
Peripheral Graphics Inc., Andover, Mass.

Filed July 12, 1973, Ser. No. 378,615

Term of patent 14 years

Int. Cl. D8—99

U.S. Cl. D8—220

Fig. 1.

Fig. 2.

Fig. 4.

Fig. 3.

Fig. 6.

Fig. 5.

FIG. 1 is a perspective view of the battery powered tape winder for punched paper tape and the like embodying the novel design;

FIG. 2 is a side elevation view of the tape winder of FIG. 1;

FIG. 3 is a front elevation view of the tape winder of FIG. 1;

FIG. 4 is a rear elevation view of the tape winder of FIG. 1;

FIG. 5 is a top view of the tape winder of FIG. 1; and

FIG. 6 is a bottom view of the tape winder of FIG. 1.

I claim:

The ornamental design for a battery powered tape winder for punched paper tape and the like, as shown.
